Primary Examiner—Antoine Duval Davis[57] CLAIM

The ornamental design for a disposable plate with cup holder, as shown and described.

DESCRIPTION

FIG. 3 is a left side elevational view of the disposable plate with cup holder of FIG. 1; the right view being a mirror image thereof;

FIG. 4 is a top plan view of the disposable plate with cup holder of FIG. 1; and,

FIG. 5 is a bottom plan view of the disposable plate with cup holder of FIG. 1.
